UNITED STATES PATENT OFFICE.

HEINRICH DEGENER, OF BERLIN, GERMANY, ASSIGNOR TO MERGENTHALER LINOTYPE COMPANY, A CORPORATION OF NEW YORK.

MATRIX FOR TYPE-SETTING AND LINE-CASTING MACHINES.

1,080,330.

Specification of Letters Patent.

Patented Dec. 2, 1913.

Original application filed March 11, 1909, Serial No. 482,845. Divided and this application filed April 20, 1910. Serial No. 556,651.

To all whom it may concern:

Be it known that I, HEINRICH DEGENER, of 26 Hollmannstrasse, Berlin, German Empire, manager, having invented certain new and useful Improvements in Matrices for Type-Setting and Line-Casting Machines, do hereby declare that the following is an exact specification of the same.

This invention relates to matrices for line setting and casting machines in which several sets of matrices arranged in separate magazines can be simultaneously used especially for such machines as described and illustrated in my United States Patent 982,172, January 17, 1911.

The essence of the present invention lies in providing the matrices with notches and recesses arranged at different positions in the different matrix-kinds and adapted to be used as distinguishing-means when the matrices after the line has been cast shall be distributed in the different magazines.

The accompanying drawing illustrates the matrices which are the object of my invention.

Figures 1 and 2 show the matrices as used in combination with a sorting device consisting of a triangular blade.

According to my prior patent especially as illustrated in Figs. 9 and 10 thereof the sorting device chiefly comprises a box, at the beginning of which is arranged a triangular blade with the point directed toward the arriving matrix line. For the purpose of engaging with said blade the matrices according to my present invention are provided with the groove 19 arranged on the bottom of the matrix body, this groove in the different matrix kinds being arranged on different points of the matrix body. Owing to the different positions of the said grooves the said blade drives the two kinds of matrices, some to the right and some to the left, namely the matrices are pushed

to the side to such an extent that the angular recesses 20 of the matrices arranged on different sides are enabled to engage with two needles as described in the patent mentioned above. It is, however, also possible to leave out the bottom recesses 19 on the matrices, if the means for sorting them engage with the upper groove 20. This construction is illustrated in Figs. 20-22 of the said patent. In this way the groove 20 is used simultaneously for the engagement with the sorting bars and the receiving needles and therefore it is necessary to form the recess partly as a straight groove as illustrated in the drawing.

Having thus fully described the nature of my invention, what I desire to secure by Letters Patent of the United States is:

1. A matrix for matrix setting and line casting machines provided with a groove arranged on the bottom of the matrix body, the position of which is different for different kinds of matrices and with a lateral angular recess for the receiving needles, the groove being adapted to engage with a sorting mechanism, shifting the different kinds of matrices laterally to such an extent that the lateral recesses are free to engage with the receiving needles.

2. A matrix for matrix setting and line casting machines provided with a groove arranged on the bottom of the matrix body, the position of which is different for different kinds of matrices and whereby they may be shifted laterally and with a lateral angular recess for the receiving needles, said recess being partly a straight groove.

In witness whereof I have hereunder set my hand in presence of two witnesses.

HEINRICH DEGENER.
